APPARATUS FOR CEMENTING WELLS

Charles O. McDowell, Fairmont, W. Va.

Application September 9, 1937, Serial No. 163,049

4 Claims. (Cl. 166—19)

This invention relates to apparatus for cementing wells.

The primary object of the invention is to provide an efficient and inexpensive device whereby a quick-setting cementitious material in a liquid or semi-liquid state may be lowered into an oil or gas well to a point where the wall of the well has caved in, the cement being released and discharged from the device under pressure at the point of cave-in so that the cement may be sprayed therefrom, impinge and become lodged against the caving surface to a predetermined, substantially uniform, thickness for forming a lining for the ruptured or slipping portion which, when hardened or set, serves as a lining to prevent further caving or inward movement of the earth.

With this and other objects in view, the invention resides in certain novel features of construction, operation and arrangement of parts which will hereinafter be fully described, reference being had to the accompanying drawing, in which—

Figure 1 is a partial vertical sectional view of a well illustrating the device positioned in a cave-in;

Figure 2 is an enlarged side elevational view of the device, parts being broken away in order to depict interior construction and arrangement of parts; and—

Figure 3 is an enlarged fragmentary detail view depicting the latch and latch release means.

Referring to said drawing, the reference numeral 1 designates a cylindrical casing having a tapered closed bottom 2 and whose upper threaded end is designed to be detachably connected to a length of pipe or a well bailer 3 by means of the coupling 4, the pipe 3, which may be of any predetermined length or capacity, serving as a hopper or reservoir for containing the supply or charge of cementitious material. A pivoted carrying bail 5 is attached to the upper open end of the hopper 3 and is designed to receive a length of cable (not shown) by means of which the apparatus is raised and lowered in the well casing 6.

An inverted conical bottom 7 is provided for the cement reservoir, the same being provided adjacent the upper end of the casing and having a port provided in its extreme bottom end. Lateral discharge ports 8 are provided in the casing directly beneath the bottom 7 at diametrically opposite points of the casing 1, although the number and position of said ports 8 may be varied as desired.

A vertically slidable tappet valve 9 is designed to register with the under side of the port of the reservoir bottom 7, the valve stem 10 being received in bearing apertures provided in spaced plates 11 and 12 located interiorly of the casing

1. A disc-like plate 13 is permanently attached to the lower end of the valve stem 10.

A fixed bracket 15 extends transversely of the casing 1 at a spaced distance beneath the valve stem 10 and has pivoted thereto an inverted L-shaped lever 16, the lower end being bifurcated and carrying on a shaft 17 a freely rotatable wheel 18. A pin 33 protrudes outwardly from each of the opposite faces of the wheel for a purpose to be hereinafter explained.

A small segmental portion of the wheel 18 extends outwardly of the casing 1 through a rectangular opening 19 provided in the casing. The upper end of the lever has provided therein an adjusting set screw 20 which, when the wheel 18 is in the position depicted in full lines in Fig. 1 of the drawing, underlies the valve stem plate 13 so as to maintain the valve in closing relation to the port. A small retractile coil spring 21 is interposed between and attached to the bracket 15 and lever 16, while a compression spring 22 encircles the valve stem 10 and is interposed between the underside of the plate 11 and a member 23 fixed to the valve stem.

Latch mechanism for maintaining the valve 9 in closed position is pivoted to the bracket 15. The latch mechanism consists of a two-piece lever 25 whose abutting ends are joined together by a flat spring 26, the upper section of the lever having a notch 30 adapted to receive therein the valve stem plate 13 and thereby support the valve 9 in closed position and being maintained in valve closing position by the provision of a spring catch 31. The bottom portion of the lower section of the lever 25 is bifurcated and straddles the wheel 18 when the latter occupies the full line position shown in Fig. 1, the extreme lower ends of the bifurcated portion terminating in an inclined angle.

Preparatory to using the device, the valve 9 is locked in the position shown in the drawing and a quantity of an appropriate cementitious material in a suitable liquid or semi-liquid state is introduced into the reservoir 3 and thereafter the device is lowered into the well by the cable attached to the bail 5 until the spraying device reaches the point of cave-in 35. As the device is being lowered into the well, that portion of the wheel 18 protruding outwardly of the casing 1 through the opening 19 frictionally engages the well casing 6 causing counterclockwise rotation of the wheel 18. With each complete revolution of said wheel its pins 33 will slightly engage the lower portion of the latch lever 25, but, due to the flexibility afforded by the spring connecting joint 26, as well as the inclined terminal end of the lever 25, the lever 25 will be permitted to be forcibly moved by the pins 33 in the same direction as the wheel rotation a sufficient dis-

tance to permit passage of the pins 33 without disturbing the valve latch.

Upon reaching the point of cave-in 35, the device is elevated a short distance in the well casing 6 so that rotation of the wheel 18 is changed to clockwise direction. During such rotation, the pins 33 will engage the side of the lever 25 opposite that engaged during counter-clockwise rotation. This results in movement 10 of both sections of the lever 25 as a unit resulting in disengagement of the valve latch 30 against the tension or resistance offered by the spring catch 31.

Following release of the valve latch, the device 15 is lowered into the cave-in area 35. At this point the wheel 18 is no longer in contact with the well casing 6 and the retractile coil spring 21 acting on the lever 16 forces the wheel 18 and the lower portion of the lever 16 outwardly 20 of the casing 1 through the opening 19. Obviously, therefore, no support is now afforded the valve 9 and the compression spring 22, together 25 with the weight of the imposed cement charge, forces the valve 9 to open position and the cementitious material gravitates from the reservoir and is discharged laterally from the device through the ports 8. The imposed weight of the cement in the reservoir results in considerable pressure at the discharge ports 8 so that 30 the cement is sprayed with considerable pressure or velocity against the surface of the cave-in and tenaciously adheres thereto for effecting a lining of cement and preventing further slippage of the earth. As hereinbefore stated, the cement 35 is preferably quick setting so that it hardens rapidly.

The device is preferably rotated and vertically reciprocated in the cave-in by means of the suspending cable in order that the entire surface 40 may receive an adequate coating of cement.

After a sufficient coating of cement is applied, the device is upwardly withdrawn from the well. Upon again entering the well casing, the wheel 18 will be pushed into its casing enclosed position 45 moving the lever 16 about its pivot to elevate the valve 9 to closed position. Thus, no cement can be discharged from the device while the same is being removed from the well.

It is thought that the invention and many 50 of its attendant advantages will be understood from the foregoing description, and it will be apparent that various changes may be made in the form, construction and arrangement of the parts without departing from the spirit and scope 55 of the invention or sacrificing all of its material advantages, the form hereinbefore described being merely a preferred embodiment thereof.

What is claimed is:—

1. In a device for cementing wells, a cylindrical casing having an opening in its wall, a reservoir for a quantity of cementitious material, a bottom for said reservoir having a discharge opening therein, lateral discharge ports in said casing beneath said reservoir bottom, a valve operable in said reservoir opening, pivoted means 60 maintaining said valve closed while said means are confined within said casing by pressure exerted thereon by the casing of the well to be cemented, said means being forced outwardly of said casing through its wall opening upon cessation of the well casing pressure for releasing said valve and permit of its opening to permit 65 the cementitious material to gravitate from said

reservoir through said bottom opening and outward of the casing through the lateral discharge ports.

2. In a device for cementing wells, a cylindrical casing having an opening in its wall, a reservoir for a quantity of cementitious material, a bottom for said reservoir having a discharge opening therein, lateral discharge ports in said casing beneath said reservoir bottom, a valve operable in said reservoir opening, pivoted means 5 maintaining said valve closed while said means are confined within said casing by pressure exerted thereon by the casing of the well to be cemented, said means being forced outwardly of said casing through its wall opening 10 upon cessation of the well casing pressure for releasing said valve and permit of its opening to permit the cementitious material to gravitate from said reservoir through said bottom opening and outward of the casing through the lateral discharge ports, and releasable latch means for locking said valve in closed position.

3. In a device for cementing wells, a cylindrical casing having an opening in its wall, a reservoir for a quantity of cementitious material, 25 a bottom for said reservoir having a discharge opening therein, lateral discharge ports in said casing beneath said reservoir bottom, a valve operable in said reservoir opening, a pivoted valve supporting lever controlling the operation of said valve, a wheel carried by the valve supporting lever and having a segmental portion protruding outwardly of the casing through its opening and frictionally engageable with the casing of a well to be cemented, said lever supporting said 30 valve in closed position while said wheel is in contact with said well casing, said wheel being free to move outwardly of said casing through its wall opening when said wheel is out of well casing contracting relation for moving said lever from valve supporting relation and permitting said valve to move to its open position to permit discharge of the material from said reservoir through said bottom opening and outward of the casing through the lateral discharge ports.

4. In a device for cementing wells, a cylindrical casing having an opening in its wall, a reservoir for a quantity of cementitious material, a bottom for said reservoir having a discharge opening therein, lateral discharge ports in said casing beneath said reservoir bottom, a valve operable in said reservoir opening, a pivoted valve supporting lever controlling the operation of said valve, a wheel carried by the valve supporting lever and having a segmental portion protruding outwardly of the casing through its opening and frictionally engageable with the casing of a well to be cemented, said lever supporting said valve in closed position while said wheel is in contact with said well casing, said wheel being free to move outwardly of said casing through its wall opening when said wheel is out of well casing contacting relation for moving said lever from valve supporting relation and permitting said valve to move to its open position to permit discharge of the material from said reservoir through said bottom opening and outward of the casing through the lateral discharge ports, and latch means engageable with said valve for maintaining the valve in closed position and adapted to be disengaged by contact with a protuberance borne by said wheel.

CHARLES O. McDOWELL.
